United States Patent Office

Des. 187,581
Patented Apr. 5, 1960

187,581

PULL

Roger P. Peterson, Grand Rapids, Mich., assignor to
Tassell Hardware Company, Grand Rapids, Mich., a
corporation of Michigan

Application April 13, 1959, Serial No. 55,474

Term of patent 14 years

(Cl. D10—8)

FIG. 1

FIG. 2

FIG. 3

FIG. 4

FIG. 5

Fig. 1 is a perspective view of a pull showing my new design, the pull being viewed from the left side and front thereof.

Fig. 2 is a front elevational view of the pull.

Fig. 3 is a plan view of said pull.

Fig. 4 is an end view of said pull.

Fig. 5 is a cross sectional view of said pull, which view is taken along the lines V—V of Fig. 3.

I claim:

The ornamental design for a pull, as shown.
